UNITED STATES PATENT OFFICE.

CARL A. MATSON, OF LYNN, MASSACHUSETTS, ASSIGNOR OF ONE-HALF TO ALBERT M. HOYT, OF SWAMPSCOTT, MASSACHUSETTS.

MACHINE FOR BURNISHING AND FINISHING THE HEELS OF BOOTS AND SHOES.

1,084,747.

Specification of Letters Patent.

Patented Jan. 20, 1914.

Application filed March 10, 1913. Serial No. 753,197.

To all whom it may concern:

Be it known that I, CARL A. MATSON, a citizen of the United States, residing at Lynn, in the county of Essex and State of 5 Massachusetts, have invented new and useful Improvements in Machines for Burnishing and Finishing the Heels of Boots and Shoes, of which the following is a specification.

10 This invention relates to a machine for burnishing and finishing the heels of boots and shoes either by the wax treating operation or by burnishing the edges of said heels after they have been colored with a suitable 15 coloring material.

The object of the invention is to provide a machine in which is embodied a work rubbing wheel which will apply wax evenly to the edges of the heels of boots and shoes and 20 which will also impart a rubbing, polishing and burnishing action to the edges of the heels of boots and shoes when they are held against it, and moreover, the invention contemplates using a wheel having a continuous, 25 yielding metallic periphery which will accommodate itself to the different curves of the edges of boot and shoe heels, together with a former which will shape the cross-sectional contour of the periphery of the 30 wheel so as to adapt the same metallic peripheried wheel to heels having different shaped or curved edges.

In the embodiment of my invention hereinafter set forth in the specification and 35 illustrated in the drawings, means are shown for applying melted wax to the periphery of the work rubbing member or wheel, said means being substantially the same as described and shown in my co-pending 40 application for Letters Patent Serial No. 734,507, filed December 2, 1912, and in this machine the heels of boots and shoes are wax treated by means of the improved wheel or work rubbing member, the wax being applied 45 in a melted condition to the periphery of the wheel and the superfluous wax being removed therefrom by means of a scraper which not only performs the operation of removing the superfluous wax from the 50 periphery of the wheel, but also shapes the periphery to fit the edges of the heels of boots and shoes which are being operated upon. It is evident, however, that if desired the wax may be applied to the periphery of

the wheel by means of a stick held against 55 said periphery, or in any of the various ways in which wax has heretofore been applied to the surface of the work rubbing wheel in this art.

It is desirable, in addition to rubbing the 60 heel circumferentially thereof in the wax treating operation to also simultaneously rub the heel transversely thereof or preferably in a direction from the heel seat toward the top lift, and it is the object of this invention to provide a wheel combined with a former which shall perform such an operation upon the edges of boot and shoe heels of different shapes which are applied to its 65 periphery.

In addition to wax treating the edges of 70 the heels of boots and shoes by means of my improved heel burnishing and finishing machine, the same may be used to burnish said edges without the use of wax—that is, it 75 may be used to impart a high luster to the edges of heels of boots and shoes of different shapes, and where the same is used without wax a coloring material is employed on the edges of the heels, such as blacking, and the 80 burnishing wheel is then utilized to burnish or polish the edge of the heel with this coloring material thereon. In either case, whether by wax treating or by burnishing a colored 85 heel my improved burnishing wheel for 85 burnishing and finishing the heels of boots and shoes imparts a high luster and smooth finish to the edge of the boot or shoe heel to which it is applied, and by means of the 90 former which shapes the periphery of the 90 wheel to fit the edge of the heel a very fine and complete burnishing or finishing is obtained, as the case may be, extending over the entire surface of the edge of the heel.

The invention, therefore, consists in a 95 machine for burnishing and finishing the heels of boots and shoes such as described in the following specification and particularly set forth in the claims.

Referring to the drawings. Figure 1 is 100 a side elevation of my improved machine for burnishing and finishing the heels of boots and shoes. Fig. 2 is a sectional elevation taken on line 2—2 of Fig. 1, both Figs. 1 and 2 being broken away to save space in 105 the drawings. Fig. 3 is a sectional elevation taken on line 2—3 of Fig. 1, a portion of a shoe being shown in connection therewith

in position to be operated upon by the work rubbing wheel. Fig. 4 is a plan view of the work-rubbing wheel.

Like numerals refer to like parts throughout the several views of the drawings.

In the drawings, 5 is the frame of the machine; 6 is the main driving shaft to which is fastened the work-rubbing wheel 7. The wax is contained in a wax pot 8 and is fed from a supply chamber 9 to an intermediate chamber 10 in which it is kept at a predetermined height by a float valve 11, the wax passing from the chamber 9 into the chamber 10 through a port 12 which is opened and closed by the float valve 11. From the chamber 10 said melted wax passes into the feed chamber 13 through a port 14. The wax is kept in a melted condition by means of a gas jet, gas being supplied by means of a pipe 15. The shaft 6 is rotated by any suitable means, such as a pulley, and the work rubbing wheel 7 which is attached to the front end of the shaft embodies a hub 16 which is fastened by a set-screw 17 to said shaft 6. The periphery of the wheel 7 is formed by a flexible member preferably consisting of a metallic strip 18 forming a helix, one end of said metallic member being fastened, preferably, by welding to a ring 19, the other end of said metallic member being fastened to an annular flange 20 which flange is fastened by means of screws 21 to a cylindrical flange 22 forming part of the hub 16. The ring 19 fits in an annular recess 23 provided in a flange 24 and is fastened thereto by means of screws 25. The cylindrical flange 22 is provided with an annular recess 26 to receive and center the flange 20. The flange 24 is provided with a hub 27 which is adjustably fastened to the hub 16 by means of a set-screw 28. The helical member 18 is thus fastened to a holder, said holder consisting of the hub 16, the flanges 24, 22 and 20 and the ring 19. It will thus be seen that the helical member constitutes the periphery of the wheel 7 and is supported upon the holder hereinbefore described, which holder is fastened to the shaft 6 by the set-screw 17 and is rotated therewith. The adjacent convolutions of the helical member 18 contact with each other, so that the wax does not penetrate to the interior of the wheel when said wheel is used as a finishing wheel, and the flanges 24 and 20, together with the ring 19, act to hold the convolutions of the helical member against lateral movement relatively to each other. By adjusting the flange 24 toward the flange 20 it will be seen that the different convolutions of the helical member 18 may be clamped against each other.

The helical member 18 is preferably formed from a tube of the proper size which is placed upon a lathe and cut so as to form the different convolutions of said helical

member. It is then placed in a lathe and its convolutions clamped against each other by any suitable means and the convex outer surface of the same is then turned thereon in said lathe. This outer surface may be made convex if so desired, but in this form of my invention it is made straight or flat, and the convex shape is given to it by a former in a manner hereinafter described. The inner diameter of the helical member is made greater than the outer diameter of the flange 22, so that a space 29 is provided in the finished wheel which allows the different convolutions of the helix to yield or move inwardly toward the median axial line of the wheel without abutting against said cylindrical flange 22.

Suitable means for heating the wheel 7 is provided, such as the gas pipe 30. It will be seen that the periphery of the wheel 7 is a continuous yielding metallic periphery and also that the periphery is resilient.

While I have described the wheel 7 as formed of metal, it will, however, be evident that any material which is hard as compared with leather and is therefore capable of polishing or burnishing leather when rubbed thereagainst would be an equivalent of metal and may be used without departing from the spirit of this invention. Such a material may be found in fiber and may be used with very good results, although not so durable and satisfactory as metal.

The wax pot 8 is provided with a cover 31 which extends partly around the wheel 7. Said cover is locked in position by means of an arm 32 which is provided with a screw 33 adapted to bear against a boss 34 on the wax pot 8. When the screw 33 is in contact with the boss 34, then the cover is locked downwardly in position over the wheel 7. When it is desired to unlock the same and throw the cover 31 backwardly upon its pivot 35, it may be done by swinging the arm 32 to one side so that the screw 33 will be disengaged from the boss 34. The cover 31 is provided with a slot 36 in which is slidably mounted a former 37. Said former is adapted to bear against the periphery of the wheel 7 and is formed on a curve corresponding to the shape of the edge of the heel which it is desired to operate upon. Said former may be moved bodily away from the wheel 7 by means of screws 38 which have screw-threaded engagement with the cover 31, as seen in Figs. 1 and 2. Said screws 38 are provided with heads 39 and are encircled by springs 40, one end of said springs bearing against the heads 39, the other end of said springs bearing against washers 41 which are seated upon the rear edge of the former 37. The screws 38 are provided with flanges 42, these flanges being hemispherical upon their outer faces, so that the former 37 may be moved toward or away

from the wheel 7 and also may be moved so as to stand at different angles to the periphery thereof by turning one of the screws 38 while leaving the other screw stationary.

- 5 By this means the former will tip to different angles relatively to the wheel, as illustrated in Fig. 3, and thus the edge of the wheel will be caused to assume different curves to fit varying edges of heels. When 70
10 the former is pressed against the periphery of the wheel 7, it being convex will cause the portion of the periphery of said wheel adjacent thereto to become concave, while that portion of the periphery of said wheel 75
15 diametrically opposite said former will be made convex or of the same curve as the edge of the former which bears against the periphery of the wheel 7.

The former, in addition to shaping the 20 edge of the wheel to fit the edge of the boot or shoe heel upon which it is desired to operate, also acts as a scraper to remove the superfluous wax from the periphery of the wheel when liquid wax is used thereon.

- 25 The former 37 is held against the periphery of the wheel to shape the same by means of the springs 40. It is, therefore, evident that if sufficient pressure is brought to bear upon the periphery of the wheel 7 by the 90
30 heel of the shoe 43, said periphery will yield slightly, being allowed so to do by the springs 40 yielding, so that the former 37 is held against the periphery of the work rubbing wheel with a yielding pressure, but 95
35 can be positively moved away from said wheel to assume different positions relatively to the periphery thereof by means of the screws 38.

The general operation of the mechanism 40 hereinbefore specifically described is as follows: The heel of the shoe 43 is placed against the periphery of the work rubbing member 7 and said work rubbing member is rotated in the direction of the arrow *a* (Fig.

- 45 1). The wax is supplied to the chamber 10 in sufficient quantity so as to keep the level thereof in the feed chamber 13 always at the height of the line *b* (Fig. 2). The wheel 7 is kept heated by a gas jet from the 105
50 pipe 30 and the wax is carried up on the periphery of said wheel until it encounters the combined former and scraper 37, when the superfluous wax is removed from the periphery of the wheel and that portion of 110
55 said wheel from which the wax has been removed then moves forward in the direction of the arrow *a* and rubs the edge of the heel of the shoe 43 which is held against it, thereby placing upon the heel a thin and even film of wax and thoroughly rubbing it and burnishing it into the edge of the heel. 115
60
65

It will be understood that the periphery of the work rubbing wheel 7, as a whole, will yield and conform to slightly varying shapes in cross sectional contour of the edges of

different heels of boots and shoes which may be applied thereto in performing the burnishing and finishing operation. It will also be understood that as the member 18 is formed as a helix, when the wheel is rotated there will be a polishing action extending circumferentially of the edge of the heel and also a tendency to lay the fibers of the leather smoothly by reason of the action of the helically disposed convolutions of the member 18 which thus stand at an angle and tend to rub the edge of the heel from the heel seat toward the top lift.

As hereinbefore set forth the former 37 can be tipped to different angles to vary the 80 cross sectional contour of the periphery of the wheel 7 and it is also evident that if the change in shape is too great to be attained by thus tipping and adjusting the former, a variety of different shaped formers can be 85 utilized of a shape to produce any shape which may be desired, from a periphery with a flat surface to one with a convex surface of as great a degree as may be desired to burnish or finish the most concave heels 90 of ladies' shoes.

After the heel has been wax treated by the work rubbing wheel 7 and an even coat of wax has been placed upon the edge of the heel and thoroughly burnished and polished 95 thereon, said heel is afterward subjected to the action of a padding roll and a brush to obtain a finer polish in a manner well known to those skilled in this art.

Having thus described my invention, what 100 I claim and desire by Letters Patent to secure is:

1. A machine for burnishing and finishing the heels of boots and shoes having, in combination, a wheel with a continuous, yielding, metallic periphery and a former adapted to bear against the periphery of said wheel, whereby the form of said periphery may be altered.

2. A machine for burnishing and finishing 110 parts of boots and shoes, having, in combination, a wheel having a continuous, resilient, metallic periphery and a convex former adapted to bear against the periphery of said wheel, whereby said periphery adjacent 115 to said former is caused to assume a concave form and that portion of said periphery diametrically opposite to said former is caused to assume a convex form.

3. A machine for burnishing and finishing 120 the heels of boots and shoes having, in combination, a wheel with a circumferentially continuous, resilient periphery and a former adapted to bear against said periphery and simultaneously change the cross sectional 125 contour of that portion of said periphery adjacent to said former and that portion of said periphery diametrically opposite to said former.

4. A machine for burnishing and finishing 130

the heels of boots and shoes having, in combination, a wheel with a continuous, yielding, metallic periphery, a former adapted to bear against the periphery of said wheel and means adapted to adjust said former toward and away from said wheel.

5. A machine for burnishing and finishing the heels of boots and shoes having, in combination, a wheel with a continuous, yielding, metallic periphery, a former adapted to bear against the periphery of said wheel and means to change the angle of said former to the periphery of said wheel laterally thereof, whereby the cross sectional contour of 15 said periphery may be varied to fit different shaped heels.

6. A machine for burnishing and finishing the heels of boots and shoes having, in combination, a wheel with a continuous, yielding, metallic periphery, a former adapted to bear against the periphery of said wheel and means adapted to hold said former against said wheel with a yielding pressure, said means including devices adapted to move 25 said former positively away from said wheel.

7. A machine for burnishing and finishing the heels of boots and shoes having, in combination, a wheel with a continuous, yielding, metallic periphery, means adapted to supply wax to the periphery of said wheel and a former adapted to bear against the periphery of said wheel, whereby superfluous wax may be removed therefrom and the cross sectional contour of said periphery at a

point diametrically opposite said former de- 35 terminated.

8. A machine for burnishing and finishing the heels of boots and shoes having, in combination, a heel burnishing and finishing wheel consisting of a strip of metal forming a helical member and constituting the periphery of said wheel, a holder for said member and a former adapted to bear against the periphery of said wheel.

9. A machine for burnishing and finishing the heels of boots and shoes having, in combination, a heel burnishing and finishing wheel consisting of a strip of material forming a helical member and constituting the periphery of said wheel, said wheel being arranged to be supplied with wax, and a holder for said helical member adapted to support said helical member with the adjacent convolutions thereof in contact with each other and a former adapted to bear against the periphery of said wheel and simultaneously remove superfluous wax from the periphery thereof and change the cross sectional contour of the periphery of said wheel at a point diametrically opposite 55 said former.

In testimony whereof I have hereunto set my hand in presence of two subscribing witnesses.

CARL A. MATSON.
